UNITED STATES PATENT OFFICE.

WARD S. IRELAND, OF OWENSBORO, KENTUCKY.

SHORTHAND-MACHINE.

1,216,998.

Specification of Letters Patent.

Patented Feb. 20, 1917.

Application filed June 28, 1915. Serial No. 36,669.

To all whom it may concern:

Be it known that I, WARD S. IRELAND, a citizen of the United States of America, a resident of Owensboro, in the county of 5 Daviess, State of Kentucky, have invented certain new and useful Improvements in Shorthand-Machines, of which the following is a full, clear, and exact description, reference being had to the accompanying drawings, forming a part of this specification.

My invention relates to improvements in shorthand machines wherein the writing is accomplished by means of a keyboard associated with mechanical printing means, and 15 more particularly to improvements in the structure of the keyboard of such a machine.

The principal object of the invention is to produce a keyboard whose operation may be accomplished with a minimum of mental and 20 physical effort, and by which the language may be written with a minimum number of strokes, and, consequently, maximum speed.

My invention particularly embodies improvements over such keyboards as were 25 early disclosed in British Patent No. 3638, of 1882, and U. S. Letters Patent No. 306,904, of Oct. 21, 1884, to Vicente Alonso de Celada. These patents disclose a keyboard comprising a plurality of keys, each 30 having a character designation thereon, there being one group of keys for writing initial consonants and prefixes of words, and another group of keys for writing final consonants and suffixes of words, and a third 35 group of keys, disposed between the two groups of keys, for writing vowels, thus enabling the operator to write at a single stroke, words containing a prefix, initial consonants, vowels, final consonants and a suffix.

One of the objects of the invention is to 40 produce a keyboard comprising a number of keys having character designations thereon, or otherwise representing characters, which are so arranged that the frequently occurring beginning and ending vowels of poly-syllabic words may be written in the same stroke in which the remainder of the word is written.

A further object of my invention is to 45 produce a keyboard comprising three groups of keys, the keys of one of said groups representing characters which are arranged in such a manner that those final consonants very frequently occurring either before, or

after, other final consonants may be combined therewith and written in the same stroke, and in either of the two relative positions. For example, in the word "help" the letter l precedes p, whereas in the word "people" the l follows the p. The characters 55 are printed line by line, one line being printed during each stroke of the keys, and each character occupies a certain fixed position in the line. Therefore, if the character l appears before p, and at no other point 60 in the final consonant group, the word "people" (written pep'l), involving the use of said characters, cannot be written in a single stroke. The structure I have disclosed includes means for printing certain 65 final consonants at more than one point in the line, for instance, l may be printed either before or after other final consonants, thus enabling the operator to print, in single 70 strokes and therefore in single lines, many 75 words which were formerly printed by operating certain keys to print the initial part of a word in one line, and then performing one or more additional key operations to print the remaining elements of the word in 80 one or more additional lines. Obviously, it is an advantage to print each word in a single line, instead of several lines, as one can more readily read a word appearing on a single line than one occupying two or 85 more lines; and furthermore a word appearing in a single line may be written in about one-half of the time required to write the same word in two lines. I am aware that attempts have been made to produce a short- 90 hand keyboard having similar character designations at different points in the final consonant group, but in so far as I am aware, such attempts have not resulted in the advantages which are derived from the final 95 consonant keys of my keyboard.

A further object of my invention is to produce a keyboard comprising three groups of keys (initial, final and medial) with the character designations of said keys so arranged that many of the characters occurring in both the initial and final groups may be struck with the corresponding fingers of each hand. I am fully aware that keyboards have heretofore been produced by which the 100 keys containing the same characters in the final and initial groups are struck with corresponding fingers of each hand; for ex-

ample, see the above mentioned Celada patents; however, my object is to produce a keyboard of this kind having certain other highly desirable features not found in the 5 patent referred to, or in any of the prior art, so far as I am aware.

My purpose is to accomplish all of the above mentioned objects without sacrificing any of the advantages gained by writing the 10 three principal subdivisions of words (prefix, stem and suffix) in the same stroke, as disclosed in the above mentioned patents.

It will be apparent that it is possible to make some changes in the arrangement of 15 key characters without departing from the invention; however, it would be impracticable in this specification to consider all of the possible variations, and the effects of such variations. Suffice it to say that although I have shown and will hereinafter 20 describe a preferred arrangement of character designations, the invention comprehends changes, variations or modifications which come within the scope of the claims 25 hereunto appended. To clearly illustrate the invention, I have shown a keyboard in which the character designations appear on the keys, but it is to be understood that the invention is not in any way limited to a 30 keyboard on which the characters actually appear, for all of the advantages of the invention could be obtained by the use of a "blind keyboard." Therefore, by the terms 35 "a key having a character designation" I mean a key for printing the character designation which may or may not actually appear on the keyboard.

Figure I is a diagrammatical view of a 40 shorthand machine, illustrating a keyboard embodying the features of my invention, and also showing the line of type characters that would be printed if all of the keys were depressed simultaneously.

Fig. II is a view of the keyboard shown 45 in Fig. I, illustrating the characters which do not have an individual key and printing means but are represented by combinations of those having an individual key and printing means.

Fig. III is a plan view illustrating a 50 modification.

Figs. IV and V are tables illustrating the component parts of words in accordance with their subdivisions in stenographic 55 writing.

Fig. VI is a table showing how the words appearing in Fig. V are written in cipher.

Fig. VII is a table showing how the missing characters are represented.

In the structure shown to illustrate the 60 preferred form of my invention, the keyboard contains 22 keys, each having a character designation and provided with means for printing said character designation when 65 the key is operated. Keys 1, 2, 3, 4, 5, 6, 7

and 8 have the following character designations, respectively: A, S, B, T, N, H, L and R, which constitute what I term the initial group. Keys 9, 10, 11 and 12 have the following character designations, respectively: A, O, E and I, which constitute what I term the middle or vowel group. Keys 13, 14, 15, 16, 17, 18, 19, 20, 21 and 22 have the following character designations, respectively: L, R, N, M, B, T, G, L, Y and S, 75 which constitute what I term the final group. The keys of the initial group are operated with the fingers of the left hand, the keys of the vowel group are operated with the thumbs of the two hands, the keys of the final group being operated with the fingers of the right hand. The keyboard is adaptable for use with a mechanical structure in which each key has a corresponding printing means and should the keys of all 80 the groups be operated simultaneously, all the letters would be printed on one line and in the following sequence:

A S B T N H L R A O E I L R N M B T G L Y S.

It is well known in the art that a word in its simplest and most representative form is composed of three principal elements; namely, an initial consonant, a final consonant, and a modifying or connecting vowel 95 member, for instance—

Initial consonant.	Vowel.	Final consonant.
M	A	N

It is true, of course, that some words are without an initial consonant, for instance—

Initial Vowel.	Final consonant.
A	T

or without a final consonant—

Initial consonant.	Vowel.
T	O

or there may be no consonant, as writing the word A or I. Speaking, however, of the general construction of a word, it contains the three above mentioned elements. Sometimes one or more of these three elements may be double or compound. For instance—

Initial consonants.	Vowels.	Final consonants.
R	OY	
P R	OU	D
R	OU	ND
C R	OW	DS.

If a word is polysyllabic, its structure is generally that of a stem (comprising the three above mentioned elements) modified by prefixes or suffixes or both. This is illustrated in Fig. IV.

There is, however, one general exception,

or addition, to the above construction of words, which is found in those polysyllabic words beginning or ending with a vowel; that is, polysyllabic words beginning or ending with a vowel and also containing at least a word stem comprising an initial consonant, a final consonant and a medial or stem vowel between said initial and final consonants. Of such words beginning with 5 vowels, about 80% begin with either A, E or I. Of those ending with vowels nearly all end with the vowel Y. Such words are illustrated in Figs. V and VI, the latter showing the words as they appear when 10 written in cipher.

It is necessary in a shorthand keyboard to have all of the keys under the immediate control of the thumbs and fingers, and this necessitates limiting the number of keys to 20 keep them under such control. It is preferable, therefore, to have as few keys as possible. In the preferred form of the invention I have limited the number of keys in the initial group to eight and those in the 25 final group to ten. The little finger of the left hand operates either the A or S separately, or both of them simultaneously by striking over the line dividing the two keys. The thumb of the left hand in like manner 30 operates the A and O keys. Thus each finger has two keys to operate, excepting the little finger of the right hand, which controls four, G, L, Y and S. This fingering may be modified to meet exigencies in writing 35 particular words.

With the initial group of keys (numbered 1 to 8 inclusive) I write all the initial elements of a word (namely, beginning vowels, prefixes and initial consonants) in their correct sequence and in the same stroke; with the middle group I write in their correct sequence (whether single or compound) the vowels that occur in the body or stem 40 of the word; and with the third or final group I write in their correct sequence and in the same stroke all the final elements of words (namely, final consonants, suffixes and ending vowels) that occur after the 45 medial vowels. This being true and being further able to operate any or all of the groups simultaneously, I am able to write with the improved structure entire words whatever their elements and in whatever sequence they may occur. By ending vowels, 50 I have reference to those sounded vowels frequently occurring as the last letter of a word having more than one syllable and not to the vowel in such words as tree, he, do, etc., the vowels in these words being 55 written with the middle or vowel group of keys.

I am aware that structures have been produced whereby to a very limited extent an ending vowel is impliedly represented in the same stroke with the stem of the word, such

as when written in a suffix by a suffix sign, as for example -ity, in quality, written KWALT, T representing the suffix -ity; or -ly, in truly, written TRUL, L representing the adverbial suffix -LY. When written in 70 this manner, however, the vowel is essentially a part of some suffix and so expressed, and not an individual designation in itself adaptable to use in correct sequence after any other final element of a word. 75

Each key comprising only one letter, and there not being sufficient keys in either group to accommodate all the letters necessary to be written by the respective groups, I have built up a cipher or code by which 80 certain characters represented by the keyboard are struck in combination and simultaneously to represent the missing letters. 85

Fig. VII represents the sequence in which the characters on the keys occur and illustrates the manner in which certain of the occurring characters combine to represent the missing characters. I mention this cipher or code for the purpose of showing the means by which the characters in my preferred arrangement operate in bringing about the results obtained. For, in considering the arrangement of the characters represented by my keyboard, it must be borne in mind they must be so arranged as to permit of not only the writing of the characters as they may appear on the keys in their correct sequence, but also that the missing characters (which those on the keyboard combine to represent) may be written in 95 their correct sequence with reference to all the character representations, whether actually represented or represented by code. In other words, the arrangement of characters on the keys must make possible a code 100 by which the missing letters may be obtained in their correct sequence both with characters represented by code and with the characters that appear on the keys. 105

For example, the table (Fig. VII) showing the cipher used with the initial group, illustrates the use of the characters NH to represent the missing letter F. NH may safely be used in combination to represent a missing letter without misreading the combination as letters beginning a word, there being no word beginning with the two consonants NH in sequence. Hence, letters used in building up the cipher must be such as will not be read as part of the 110 regular spelling or sound of the word, instead of the character their combination represents. It will be further observed that the letter F in the initial part of the word combines with L or R following it (flow and 115 from) or with S preceding it as in sphere (ph having the phonetic value of F). For like reasons are the given cipher representations for the other missing characters preferably in accordance with the table shown 120 125 130

in Fig. VII. I have thus fully explained the improvement of the cipher for representing missing letters for the purpose of showing the value of arranging the characters in my structure in the manner shown, and to point out the importance of such an arrangement in enabling me to write any or all the elements of a word in a single stroke. That is, to write beginning or ending vowel or both in the same stroke with initial consonants, prefixes, final consonants, and suffixes or either of them.

It is obvious that in selecting the letters which the keys of the initial group are respectively to designate, I have arranged the characters in the order in which they occur in the various known initial combinations of words or word stems. For example, words or syllables frequently begin with the combinations as or ast (assert—astound) but not with tsa. Words also begin with pl or br (play or bring) but not with lp or rb. I, therefore, place these letters in a sequence that will enable me to write them in their known sequences. In like manner do the middle and final groups contain the preferred arrangement of characters.

Vowels frequently occur at the beginning of words, before the initial consonant or consonants, or even before the prefix, and the vowels which I have arranged in the initial group preferably appear at the beginning of the group. This arrangement is preferable because it enables me to write a beginning vowel in the same stroke with the remainder of the word, it being observed that vowels occurring after the initial consonants may be written by means of the middle group.

Heretofore, the practice in this art has been to write a beginning vowel (one occurring before an initial consonant) with the middle or vowel group of keys in one stroke on one line, and to continue the writing of the word in a succeeding stroke and on the succeeding line. For example, in the word "attempt", the structures of the prior art would write the vowel A in one stroke and the remainder of the word in a succeeding stroke. It will thus be seen that, having arranged the characters on the keys of the initial group in such a manner as to permit the writing of beginning vowels in the same stroke with the initial consonants of words, I save many strokes of the keyboard in writing many very ordinary words, and consequently, enable the operator to write more speedily.

In the same manner am I able to write with the final group of letters, and in the same stroke with the remainder of the word, terminal or ending vowels in their correct sequence. I have included in my preferred structure the vowel Y, as Y is the only vowel

used terminally except in a comparatively limited number of words, and this is frequently used as i also, as in the word notice written NOTYS, read NOTIS or notice. I also consider this a very valuable feature of my improved structure, for the structures of the prior art require an additional stroke in writing this vowel when it occurs at the end of a word. For example, in such words as "story" "weary", etc., the structures of the prior art, not being provided with ending vowels, require an additional stroke in order to write the vowel Y with the middle group of keys. It will thus be seen that in this manner my improved structure again renders possible a greatly increased speed.

While I have shown a preferred structure, I do not wish to be limited to the exact arrangement disclosed, but it should be understood that variations can be made thereon without materially decreasing the effectiveness of my invention. For instance, as shown in Fig. III, I might add at the beginning of my keyboard two keys representing the vowels O and U which may be combined to represent E. These two keys would be operated by the little finger of the left hand. What I have endeavored to set forth, is a structure which will effect a very great saving in time by writing beginning or ending vowels in the same stroke with the other elements of words.

A study of the tables illustrated in the drawings will show that I am able to write at a single stroke, the vowels and consonants in the various sequences in which they occur in words, and that I am able to write at a single stroke beginning vowels, initial consonants, medial or stem vowels, final consonants, and terminal vowels of words. I have thus shown that I can write the words of the English language, including their three elementary parts (initial consonants, vowels and final consonants) in a single stroke, and likewise word stems as well as beginning and ending vowels, in so far as such words and word stems conform to their most frequent construction.

In a manner like unto that of representing the missing characters in the initial and final groups I use certain representations for prefixes and suffixes of words, using for my prefix combinations characters occurring on keys of the initial groups and for my suffix combinations characters occurring on the keys of the final group. By prefixes or suffixes of words is meant those initial or final terminal syllables which are common to many words, such as PRE-, COM-, TION-, ING-, etc., Figs. IV, V and VI.

Another very important feature of my new keyboard is the arrangement of the letters in the final group. A study of the sequence in which the consonants occur in

words will make it obvious that any two initial consonants occurring in combination have only one sequence with reference to each other. For example, S in combination with another consonant at the beginning of a word always precedes the consonant with which it combines, while L or R, for instance, always follow the consonant or consonants with which they combine, and so in all such combined initial consonants there is only one sequence. This is by no means true, however, with reference to the consonants that end words. For instance, L would precede P in the word help, but follow it in the word people or chapel, (it not being necessary to write the e in such a word as chapel, its sound being represented in the consonant L, and in writing stenographically it is the practice to omit silent and unnecessary letters. Other examples would be in the words cannon (two final N's), barren (N following R), banner (N preceding R) chisel (S preceding L), chills (L preceding S). By an extensive and exhaustive search it develops that certain letters among the final consonants are thus found in different relative positions. This idea of two final consonants having two sequences with reference to each other appears to apply to certain particular letters, particularly L, R and N, but will also be quite extensively found with reference to S and D, largely on account of the use of these two letters in the inflection of words. When S occurs in combination with another consonant to form a compound final consonant it usually precedes the other consonant except in instances where it forms the plural of nouns (tribes) or the singular third person of verbs (he kills). One of the most frequent uses of D when used following another final consonant is in the past tense of verbs, although it does occur both before and after other consonants when used terminally, as bidden and bind, still it might be observed that, even in these two instances, the letter N brings about the double sequence. In final consonants D usually follows the consonant with which it combines, unless its combining consonant is L, R or N.

It will be observed from the structure of the final group that I am able to write in their correct sequence and in the same stroke L, N, R, S, or D with whatever consonant they combine as final consonants.

By constructing the keyboard in this manner, I enable the operator to write the same final consonant in different positions with respect to other final consonants. This is quite important for, as previously pointed out, certain final consonants may appear either before or after other final consonants, and if the final consonant group did not include the proper consonants at two different points, it would be necessary in many in-

stances to write the second of the two consonants in an additional stroke, or to have a specific combination or code to represent them. For example, where a keyboard of the prior art would be able to write L after P as in the word "people;" in writing the word help, it would be necessary on such a keyboard to write hel in the first stroke and p in the second stroke; whereas, in my improved structure I am able to write l in the same stroke with p, whether it precedes or follows the p. The same remarks would apply to chisel and chills; in fact, to a very extensive list of very frequently occurring words. Again I am enabled by my structure to eliminate many strokes of the operator, and thereby effect greater speed.

Although by the use of arbitrary code characters or by using certain combinations of keys for individual sequences not otherwise obtainable (as for lp in the foregoing illustration) it may be possible to obtain a few of the double final sequences on the prior keyboards, this possibility is so restricted by the combination and arrangement of characters on the former keyboards, that I believe it is quite impossible, with such keyboards, to gain any great advantage by such an essentially large use of arbitrary combinations.

It is further obvious that I am likewise able to write with my initial group, beginning vowels, prefixes and initial consonants in the same stroke, and with my final group, final consonants, suffixes and ending vowels in the same stroke.

Since the main purpose of shorthand machines is to save time and labor by writing words very quickly and in the fewest possible number of strokes, it will be apparent that my new structure includes several highly desirable new features. The vowel key or keys preceding initial consonant keys involves a new combination and arrangement of parts, whereby many frequently occurring words formerly requiring a multiplicity of strokes, may be written in single strokes. A similar advantage is gained by the new arrangement and combination of elements producing the final group of keys, and inasmuch as speed is one of the primary and very essential characteristics of shorthand writing, the advantages resulting from the new combination and arrangement of elements will be readily appreciated. Moreover, it is important to note that I have gained all of these advantages by the use of a convenient number of keys under the immediate control of the fingers and thumbs of the operator.

I claim:

1. In a shorthand machine, a keyboard, comprising a plurality of keys having character designations and arranged in such sequence that a beginning vowel may be writ-

- ten in the same stroke with the stem of the word.
2. In a shorthand machine, a keyboard, comprising a plurality of keys having character designations and arranged in such sequence that an ending vowel may be written in the same stroke with the stem of the word.
3. In a shorthand machine a keyboard comprising a plurality of keys having character designations arranged in such sequence that both a beginning and an ending vowel may be written in the same stroke with the stem of the word.
4. In a shorthand machine a keyboard comprising a plurality of keys having character designations arranged in such sequence that a beginning vowel and a prefix may be written in the same stroke with the stem of the word.
5. In a shorthand machine a keyboard comprising a plurality of keys having character designations and arranged in such sequence that a suffix and an ending vowel may be written in the same stroke with the stem of a word.
6. In a shorthand machine a keyboard comprising a plurality of keys having character designations and arranged in such sequence that a beginning vowel and a suffix may be written in the same stroke with the stem of the word.
7. In a shorthand machine a keyboard comprising a plurality of keys having character designations and arranged in such sequence that a prefix and an ending vowel may be written in the same stroke with the stem of the word.
8. In a shorthand machine a keyboard comprising a plurality of keys having character designations representing in a single stroke a beginning vowel and the stem of a word.
9. In a shorthand machine a keyboard comprising a plurality of keys having character designations representing in a single stroke an ending vowel and the stem of a word.
10. In a shorthand machine a keyboard comprising a plurality of keys having character designations representing in a single stroke both a beginning and an ending vowel and the stem of a word.
11. In a shorthand machine, a keyboard, comprising three groups of keys, the keys of one of said groups containing character designations arranged in such a sequence that, either singly or in combination, they are indicative of beginning vowels and initial consonants when written either separately or in combination with each other.
12. In a shorthand machine, a keyboard, comprising three groups of keys, the keys of one of said groups containing character designations arranged in such a sequence that, either singly or in combination, they are indicative of ending vowels and final consonants, when written either separately or in combination with each other.
13. In a shorthand machine, a keyboard, comprising three groups of keys, the keys of one of said groups containing character designations arranged in such a sequence that, either singly or in combination, they are indicative of beginning vowels and initial consonants, when written either separately or in combination with each other; another of said groups containing character designations arranged in such a sequence that, either singly or in combination, they are indicative of ending vowels and final consonants, when written either separately or in combination with each other; and a third group of keys containing character designations arranged in such a sequence that, either singly or in combination, they are indicative of vowels and diphthongs.
14. In a shorthand machine a keyboard comprising a plurality of keys having character designations which by means of their relative locations and the employment of a cipher represent in a single stroke a beginning vowel and the stem of a word.
15. In a shorthand machine a keyboard comprising a plurality of keys having character designations which by means of their relative locations and the employment of a cipher represent in a single stroke an ending vowel and the stem of a word.
16. In a shorthand machine a keyboard comprising a plurality of keys having character designations which by means of their relative locations and the employment of a cipher represent in a single stroke both a beginning vowel and an ending vowel and the stem of a word.
17. In a shorthand machine, means for writing a line of characters at a single stroke, said means including a series of initial consonant keys, a series of final consonant keys, a series of medial vowel keys for writing vowels between the initial and final consonants, and a beginning vowel key preceding said initial consonant keys.
18. In a shorthand machine, means for writing a line of characters at a single stroke, said means including a series of initial consonant keys, a series of final consonant keys, a series of medial vowel keys for writing vowels between the initial and final consonants, and an ending vowel key adapted to write in a single stroke a vowel following said final consonants.
19. In a shorthand machine, means for writing a line of characters at a single stroke, said means including a keyboard having an initial group of keys comprising initial consonant keys and a primary vowel key preceding said initial consonant keys and adapted to print a vowel before initial consonants, a final group of keys comprising final consonants.

- consonant keys and an ending vowel key following said final consonant keys and adapted to write a vowel after the final consonants, and a group of medial vowel keys arranged to write vowels between the initial and final consonants.
20. A shorthand machine, having a keyboard, comprising a group of initial consonant keys, a group of final consonant keys, a group of medial or stem vowel keys, and a vowel key preceding said initial consonant keys, adapted to write in their correct sequence in a single stroke a beginning vowel, an initial consonant, a stem vowel, and a final consonant.
21. A shorthand machine, having a keyboard, comprising a group of initial consonant keys, a group of final consonant keys, a group of medial or stem vowel keys, and a vowel key following said final consonant keys, adapted to write in their correct sequence in a single stroke an initial consonant, a stem vowel, a final consonant, and an ending vowel.
22. In a shorthand machine, having a keyboard, comprising a group of initial consonant keys, a group of final consonant keys, a group of medial or stem vowel keys, and a key containing a Y or I designation, following said final consonant key.
23. In a shorthand machine, a keyboard, comprising a plurality of keys, having character designations for writing vowels and initial and final consonants of words, certain of said final consonants being indicative of certain final consonants occurring twice and at different points in the same stroke.
24. In a shorthand machine, a keyboard, comprising a plurality of keys, having character designations for writing vowels and initial and final consonants of words, certain of said final consonants being indicative of certain final consonants occurring twice and in a before and after relation with certain other consonants with which they combine when written in the same stroke.
25. In a shorthand machine, a keyboard comprising a plurality of keys having character designations arranged in such sequence that vowels and initial and final consonants of words may be printed in the same stroke, said final consonants containing two designations for final consonants occurring either before or after or both before and after other final consonants with which they combine, so that said final consonants occurring twice may be written either before or after the consonants with which they combine.
26. In a shorthand machine, a keyboard comprising a plurality of keys having character designations arranged in such sequence that final consonants having a before and after relation with other consonants may be written in a single stroke in either or both of said relations with other consonants.
27. In a shorthand machine, a keyboard comprising a plurality of keys having character designations arranged in such sequence that final consonants having a before and after relation with other final consonants may be written in the same stroke in either or both of said relations with said other consonants without the use of arbitrary code designations for individual sequences.
28. In a shorthand machine means for writing a line of characters at a single stroke, said means including a keyboard having initial and final consonant keys, and medial vowel keys between said initial and final consonant keys, said final consonant keys including pairs of keys, the keys of each pair being adapted to write at a single stroke character designations representing the same final consonant at different points with respect to the other final consonants with which it combines.
29. In a shorthand machine, a keyboard, comprising three groups of keys, one of said groups having character designations indicative of final consonants and comprising L, N and R in a relation both before and after the final consonants with which said L, N and R have a before and after relation when written in the same stroke.
30. In a shorthand machine, a keyboard, comprising three groups of keys, one of said groups having character designations indicative of final consonants and comprising L, N and R in a relation either before or after, or both before and after, the final consonants with which said L, N and R have a before and after relation when written in the same stroke.
31. In a shorthand machine, a keyboard, comprising three groups of keys, one of said groups having character designations indicative of final consonants and comprising L, N, R, S and D in a relation both before and after the final consonants with which said L, N, R, S and D have a before and after relation when written in the same stroke.
32. In a shorthand machine, a keyboard, comprising three groups of keys, the keys of one of said groups representing characters arranged in such a manner that those final consonants frequently occurring either before or after other final consonants may be combined in their correct relation therewith and written in the same stroke.
33. In a shorthand machine, a keyboard including a group of letters

B N L
S T H R

arranged at one side of the center of the keyboard and representing singly and in

combination, initial consonants and prefixes of words.

34. In a shorthand machine, a keyboard comprising an initial group of letters

5 A B N L
S T H R

having the sequence

10 A S B T N H L R

for writing the initial part of a word.

35. In a shorthand machine, a keyboard having a group of letters

15 L N B G
R M T L S

arranged at one side of the center of the keyboard and representing singly and in combination, final consonants and suffixes of

20 words.

36. In a shorthand machine, a keyboard comprising a final group of letters

25 L N B G Y
R M T L S

having the sequence

L R N M B T G L Y S

for writing the final part of a word.

30 37. In a shorthand machine, a keyboard comprising a group of letters

B N L
S T H R

35 arranged at one side of the center of the

keyboard and representing singly and in combination, initial consonants and prefixes of words; another group of letters

40 L N B G
R M T L S

at the other side of the center of the keyboard and representing singly or in combination, final consonants and suffixes of words, and a medial group of vowels 45 A O E I

38. In a shorthand machine, a keyboard comprising an initial group of keys having the character designations.

50 A B N L
S T H R

having the sequence

A S B T N H L R

and a final group of keys having the character designations

55 L N B G Y
R M T L S

having the sequence

L R N M B T G L Y S

and a third, or medial, group of keys

60 A O E I

in the same sequence.
